UNITED STATES PATENT OFFICE

WILLARD E. KING, OF DOWNTON GROVE, ILLINOIS

PUMP

Application filed June 13, 1929. Serial No. 370,589.

My invention relates to pumps of the type involving a rotary piston or impeller arranged, preferably, eccentrically in a cylindrical chamber, to which the liquid, lubricating oil, for example, is drawn, and from which it is expelled by action of the impeller.

One of the objects of the invention is to provide certain improvements in a pump of this type whereby the pressure of the outgoing fluid may be increased without increasing the velocity of the impeller.

Another object is to provide means whereby the tendency of the pump to whip the liquid, especially in the case of a lubricating oil, to a froth, thereby lessening or stopping entirely the flow of the oil, is counter-acted and the operation of the pump at high efficiency is assured.

Further objects of the invention are to provide certain novel and improved constructions, devices and arrangements for a pump of this type which will obviate the necessity of using packing in connection with the moving parts; which will reduce to a minimum end thrusts, that is, pressure along the axis of the rotor element; and which will permit the impeller parts to yield, in case of a stoppage in the pressure line, while the rotor continues to turn. Other incidental objects will be referred to in the following description of the preferred embodiment of the invention disclosed in the drawings.

Referring to the drawings:

Fig. 1 is an end view of the pump with the end or cover plate removed to show the working parts of the pump.

Fig. 2 is a longitudinal sectional view on line 2-2 of Fig. 1, but showing the cover plate in place.

Fig. 3 is a cross-sectional view of the pump casing taken on a plane parallel to the plane of Fig. 1, showing a part of the rotor.

Fig. 4 is a sectional view on line 4-4 of Fig. 1, the rotor being omitted.

Fig. 5 is a fragmentary sectional view on line 5-5 of Fig. 1.

Fig. 6 is a view in perspective of the rotor.

Fig. 7 is a similar view of the reciprocating piston or impeller.

Fig. 8 is a similar view of one of the sealing lugs for the reciprocating piston.

Fig. 9 is a view similar to Fig. 1, but showing the moving parts in positions different from those of Fig. 1, and

Fig. 10 is a sectional view, but with the cover plate in place, on line 10-10 of Fig. 9.

In the pumps of the type referred to, which, when the rotary impeller is not provided with blades, are sometimes designated "cam type" pumps, the rotation of the eccentrically placed piston or impeller creates suction and pressure spaces in the pump chamber, one of which increases as the other diminishes; the oil or other liquid being drawn into the space of increasing volume, which is then a suction space, and is swept out of this space, by the turning of the impeller, as the space diminishes from maximum to minimum volume. In a pump operating on this principle the pressure created depends upon the velocity with which the rotor sweeps the liquid through the diminishing pressure space and out through the discharge outlet. If, however, the impeller is given a very high velocity, oil or a liquid of that character is likely to be whipped to a froth, with the result that the pump ceases functioning.

According to my invention, the pump is provided, in addition to the rotary impeller, with a reciprocating impeller or piston which creates a pressure in a secondary pressure chamber, so as to force liquid from said secondary chamber into the main pump chamber on the pressure side of the rotary impeller, thereby accomplishing two functions: the increase of fluid pressure at the eduction port of the pump and the injection into the oil body subject to the whipping or whirling action of the rotary impeller, of a body of

oil which has not been subject to any such whipping action, so that if there be any tendency of the liquid body to be frothed by action of the rotary impeller, this tendency is counter-acted and the pump kept filled with sufficient liquid at the density necessary to insure the proper and efficient operation of the pump.

This principle of operation could be embodied, it is conceived, in a variety of different mechanical forms. In the preferred embodiment of the invention illustrated in the drawings hereto appended, the reciprocating impeller is carried by the rotary impeller 19 and is reciprocated, due to the eccentricity of the rotary impeller with respect to the chamber in which it operates, by contact with the circumferential wall of said chamber; and the pump casing is provided with an inner chamber, which will be referred to as a secondary pressure chamber, divided into two spaces by a web on the shaft of the rotor, the term "rotor" being intended to designate the rotary structure or element of the pump as a whole. The reciprocating impeller draws oil from each of the spaces of the secondary chamber, in alternation while such space is filling, and then forces it back into the said spaces while the space is cut off from the inlet, creating a pressure which, when said space is ported to the main pump chamber drives a stream of oil into the whirling stream of oil under compression by the rotary impeller, thereby accomplishing the two functions above referred to. In the particular arrangement shown in the drawings, the reciprocating impeller also creates a direct pressure, by displacement, against the body of oil on the compression side of the rotary impeller. That is, the reciprocating impeller works in the main pump chamber and is timed to supplement the displacement effected by the rotary impeller, thereby increasing the pressure of the outgoing fluid stream. In the same way, in an inverse sense, the reciprocating impeller increases the suction produced, on its suction side, by the rotary impeller.

It is realized that the principle of the invention might be embodied in mechanical constructions quite different from that shown in the drawings and referred to in the above brief summary. Therefore I wish to be understood as intending to cover by patent all modifications and structural variations of the illustrated embodiment within the scope of the appended claims.

Referring to the drawings, 10 designates a casing formed to provide a main pump chamber 11 and a secondary pressure or pump chamber 12. 13 (Fig. 6) is a rotor comprising: a shaft 14, extending through a stuffing box 15 on the end wall 16 of the casing 10; a circular web 17 which lies against the inner wall of the housing; a partition web 18

in line with the axis of the rotor which extends across the secondary pressure chamber 12; and a head or rotary impeller 19, which lies within the main pump chamber 11 and is formed with a slide-way 20, with a web 21 extending across the slide way, and with ports 22, 23 on opposite sides of web 21. The rotor is arranged so that the impeller 19 is eccentrically placed in the main pump chamber 11; *a* indicating in Fig. 1 the center of the chamber and *b*, the axis of the rotor.

Arranged in the slideway 20 of the rotary impeller 19 is a reciprocating impeller 24 (Fig. 7) recessed at 25 to extend over the cross web 21 of the rotary impeller and with its upper surface 26 flush with the upper surfaces of the end members 27, 27 of the rotary impeller. The recess 25 is considerably wider than the width or thickness of the web 21, permitting lengthwise movement of the impeller 24. The impeller 24 is formed with notches 28 in opposite ends for sealing blocks 29^a, 29^b, which are pressed outwardly against the circumferential wall 30 of the main pump chamber by coiled springs 31 arranged in sunken spring seats 32 in the notches 28. A cover plate 33 is secured to casing 10 by screws 34.

A nipple 35, which will be referred to as an inlet duct (although the pump connections might be reversed with a counter-clockwise rotation of the rotor) is tapped into the side wall of the casing 10 so as lead to the secondary pressure or pump chamber 12. The wall of the casing is formed at this point with a groove or passage 36, leading also from the inlet 35 to the main pump chamber 11. Diametrically opposite the passage 36 also in the casing wall is another groove or a port 37 forming a by-pass connecting chambers 11 and 12. An outlet nipple 38 is tapped into the side wall of the casing so as to communicate with the main pump chamber 11. The circumferential wall of chamber 11 is preferably grooved or cut away adjacent outlet 38, as indicated at 39. The outlet nipple 38 is preferably of smaller diameter than the inlet nipple 35.

Operation.—It will be assumed that the rotor is in the position shown in Figs. 1, 2 and 3, and is moving in a clockwise direction, as indicated by the arrow, Fig. 1. This movement of the rotor has caused the oil to be drawn from inlet nipple 35 through port 36 into the space 11^a on the suction side of the rotary impeller. This continues until port 36 is closed by the sealing block 29^b, the space 11^a becoming gradually larger and larger, until it reaches its maximum size, when the rotor is about in the position shown in Figs. 9 and 10. The liquid in the main pump chamber 11 which is in advance of the sealing block 29^a is being swept around toward the eduction port 38 of the pump 130

through a pressure space 11^b which is gradually diminished and disappears, substantially, when the rotor reaches the position of Figs. 9 and 10. The spaces 12^a, 12^b are filled 5 with oil replenished as they pass the inlet duct 35 through operation of the reciprocating impeller 24, as will be described.

Referring again to Figs. 1, 2 and 3, the reciprocating impeller 24 is shown in one extreme position providing a space 25^a constituting an auxiliary pumping chamber in the slide way 20 of maximum width within the impeller and on one side of the cross web 24 and providing only a small cushioning space 15 25^b on the other side of the web 21 in the slideway 20. The space 25^a has been filled with oil from space 12^a through port 23, by the suction produced by the previous movement of impeller 24. As the rotary impeller 20 rotates from the position shown in Fig. 1, toward the position shown in Fig. 9, the reciprocating impeller 24 is moved to the right (Fig. 2) to compress the oil in space 25^a. Back pressure on the inlet duct 35 is cut off 25 by web 18 passing this duct; and, as soon as this web opens duct 37, the oil theretofore compressed by pressure through port 23 from space 25^a in the space 12^a is forced up through port 37 into the space 11^b on the pressure side of the rotary impeller. In 30 Figs. 9 and 10, the reciprocating impeller 24 is shown in an intermediate position. The impeller is moving to the left (Fig. 10) and oil is flowing from the space in the secondary chamber 12 on one side of web 18 into the auxiliary pumping space 25^a in the reciprocating impeller. The oil in space 25^b is being forced into the space in the secondary chamber 12 on the other side of web 18 to 35 create a pressure in said space which will be relieved when this space is opened to the by-pass duct 37. With the rotor in the position shown in Figs. 9 and 10, both passages 36 and 37 are covered. The dividing web in chamber 12 is in the position shown in dotted lines (Fig. 3).

In case of a stoppage in the discharge line connected with nipple 38, the sealing blocks 29^a, 29^b will yield against their springs, some 50 clearance existing between the blocks and reciprocating impeller at all positions of the impeller. Thus the pump will not be called upon to carry a load which might endanger it and, moreover, the maximum pressure 55 which the pump is capable of developing can be regulated by providing springs 31 of such stiffness as may be required.

The function of the circular web 17 is to 60 relieve the cover plate 33 of end thrust by the rotor since this web 17 receives the downward thrust and is like the rotor rigidly fixed on the shaft. The moving parts of the pump require no packing. The liquid leaking back over the upper face of the rotor

and impeller under the cover 33 acts as a packing and also as a cushioning means.

It will be observed that the reciprocating impeller performs two functions: It acts as a reciprocating piston in slideway 20, alternately drawing in and expelling liquid therefrom through ports 22 and 23 and thus exerts pressure on the liquid in the secondary chamber 12 causing the liquid from chamber 12 to be forced into the main pump chamber on the pressure side of the pump; and it also acts, by displacement, to exert of itself a direct pressure upon the liquid being expelled from the main pump chamber. That is, as the space 11^b (referring to Fig. 1) is diminished by the rotation of the rotary impeller, it is still further diminished by the straight line movement of the reciprocating impeller, the two impellers acting together to produce a very rapid displacement of the liquid on the pressure side of the pump. The two impellers operate in just the reverse manner to increase the suction of the pump by producing a rapid increase in the size of the space on the suction side of the rotor. 70 The oil packing between the rotor structure and the casing and its cover plate results from the fact that the leakage streams of oil from the two impellers are opposed one to another, that is, the leakage up from the auxiliary pumping chamber in slideway 20 meets the leakage from the main pump chamber flowing back over the upper faces of members 27 on the rotor, to thus provide 75 a liquid seal and cushion.

I claim:

1. In a pump, the combination of a casing providing a main pump chamber and a secondary chamber; a rotor in said chambers comprising a shaft, a web extending diametrically across the secondary chamber and an impeller head eccentrically arranged in said main chamber and formed with a slide way, with a cross web and with ports on opposite sides of the cross web connecting the slide way with the secondary chamber; a combined reciprocating impeller and valve in said slide way and extending across said cross web; said casing being formed with an inlet port therethrough communicating with the main and secondary chambers, a by-pass port between the secondary chamber and the main chamber and an outlet port through the casing communicating with the main chamber.

2. In a pump, the combination of a casing providing a main pump chamber and a secondary chamber; a rotor in said chambers comprising a shaft, a web extending diametrically across the secondary chamber, and an impeller head eccentrically arranged in said main chamber, said impeller head being formed with a slide way, a cross web and ports on opposite sides of the cross web connecting the slide-way with the secondary

chamber; and a reciprocating impeller and valve in said slide way extending across said cross web; said casing being formed with an inlet port leading to the secondary chamber, 5 a passage from said port to the main chamber, a by-pass port from the secondary chamber to the main chamber and an outlet port from the main chamber.

3. In a pump, the combination of a casing 10 providing a main pump chamber and a secondary chamber; a rotor in said chambers comprising a shaft, a web extending diametrically across the secondary chamber, a circular web at the inner end of the secondary 15 chamber concentric therewith and an impeller head eccentrically arranged in said main chamber, said impeller head being formed with a slide way, a cross web therein and ports on opposite sides of the cross web 20 connecting the slide-way with the secondary chamber; and a reciprocating impeller and valve in said slide way and extending across said cross web; said casing being formed with an inlet port leading to the secondary 25 chamber, a passage from said port to the main chamber, a by-pass from the secondary chamber to the main chamber and an outlet port from the main chamber adjacent said by-pass whereby the total discharge pressure 30 is increased and the said circular web receives the axial thrust of the pump to provide substantial axial balance for the rotor.

4. In a pump, the combination of a casing 35 providing a main pump chamber and a secondary chamber; a rotor in said chambers comprising a shaft, a web extending diametrically across the secondary chamber and an impeller head eccentrically arranged in said main chamber, said impeller head 40 being formed with a slide way, a cross web therein and ports on opposite sides of the cross web connecting the slideway with the secondary chamber; and a reciprocating impeller and valve in said slide way and extending across said cross web operated by 45 contact with the circumferential wall of the main chamber; said casing being formed with an inlet port communicating with the main and secondary chambers, a by-pass port 50 between the secondary chamber and the main chamber and an outlet port through the casing communicating with the main chamber.

5. In a pump, the combination of a casing 55 providing a main pump chamber and a secondary chamber; a rotor in said chambers comprising a shaft, a web extending diametrically across the secondary chamber and an impeller head eccentrically arranged in said 60 main chamber, said impeller head being formed with a slide way, a cross web therein and ports on opposite sides of the cross web connecting the slide-way with the secondary chamber; a reciprocating impeller and valve 65 in said slide way and extending across said

70 web operated by contact with the circumferential wall of the main chamber; and sealing lugs movable at the ends of the reciprocating impeller; said casing being formed with an inlet port communicating with the main and secondary chambers, a by-pass port between the secondary chamber and the main chamber and an outlet port through the casing communicating with the main chamber.

6. In a pump, the combination of a casing 75 providing a main pump chamber and a secondary chamber; a rotor comprising an operating shaft, a web extending diametrically across the secondary chamber, a circular web at the inner end of the secondary chamber, and an impeller head on said shaft eccentrically arranged in said main chamber said impeller head being formed with a slide way, a cross web therein and apertures on opposite sides of the cross web connecting the 80 slideway with the secondary chamber; and a reciprocating impeller and valve in said slide way and extending across said cross web operated by contact with the circumferential wall of the main chamber; sealing lugs movable at the ends of said reciprocating impeller; and an end cover for the casing said 85 casing being formed with an inlet port communicating with the main and secondary chambers, a by-pass port between the secondary chamber and main chamber and an outlet port from the main chamber, said circular web serving to relieve axial thrust of the rotor against the end walls of the casing.

7. In a pump, a casing containing a main 90 pump chamber and a secondary chamber, a rotor mounted in the chambers and comprising a web dividing the secondary chamber into high and low pressure chambers, and a head eccentrically positioned in the main pump chamber, a slide carried by the head and functioning as a rotary impeller in the main pump chamber and as a reciprocating impeller for alternately applying pressure to the liquid in the two secondary pressure 95 chambers, a liquid inlet communicating with the main and secondary chambers, a discharge outlet leading from the main chamber, and a discharge passage leading from the secondary to the main chamber so positioned that the reciprocating impeller will force liquid from the secondary chamber into the main pump chamber on the pressure side of the rotary impeller after the impeller approaches the outlet for the discharge of liquid 105 from the main chamber.

8. In a pump, a casing containing a main 110 pump chamber and a secondary chamber, a rotary head positioned eccentrically in the main pump chamber, a slide carried by the head and functioning as a rotary impeller in the main pump chamber and as a reciprocating impeller for applying pressure to the liquid in the secondary chamber, a liquid inlet communicating with the main and sec- 115 120 125 130

ondary chambers, a discharge outlet leading from the main chamber, and a discharge passage leading from the secondary chamber to the main chamber and so positioned that the 5 reciprocating impeller will force liquid from the pressure chamber into the main pump chamber on the pressure side of the rotary impeller at a point adjacent the discharge outlet, whereby the total discharge pressure 10 is increased and leakage from the secondary chamber opposes leakage from the main chamber to provide a fluid seal for the pump.
